CLAIM

The ornamental design for a fender extension, as shown and described.

DESCRIPTION

FIG. 1 is an isometric view of a fender extension according to our new design;

FIG. 2 is a front view of the fender extension of FIG. 1;

FIG. 3 is a top view of the fender extension of FIG. 1;

FIG. 4 is a left side view of the fender extension of FIG. 1;

FIG. 5 is a right side view of the fender extension of FIG. 1; and,

FIG. 6 is a cross-sectional view taken along line 6-6 in FIG. 2. The broken lines show portions of the fender extension which form no part of the claimed design.

FIGS. 1-6 illustrate a first embodiment of our novel design suitable for use on one side of a vehicle. Our novel design also includes a second embodiment suitable for use on the opposite side of a vehicle, which is mirror symmetrical to FIGS. 1-6 and therefore not separately illustrated.
